(57) **CLAIM**

The ornamental design for a car mount for electronic device, as shown and described.

DESCRIPTION

FIG. 1 is a front perspective view of a car mount for electronic device, showing my new design;

FIG. 2 is a rear perspective view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front perspective view thereof, shown in a first alternate configuration with the arm portion of the car mount for electronic device rotated for clarity of disclosure;

FIG. 9 is a front perspective view thereof, shown in a second alternate configuration with the arm portion of the car mount for electronic device rotated and extended for clarity of disclosure; and,

FIG. 10 is a front perspective view thereof, shown in a third alternate configuration with the arm portion of the car mount for electronic device extended for clarity of disclosure.

The dash-dash broken lines in the drawings depict part of the car mount for electronic device that form no part of the claimed design. The dash-dot broken lines in the drawings depict the bounds of the claim and form no part of the claimed design.
